AMOS VERNER JENSEN, OF CEDAR FALLS, IOWA, ASSIGNOR TO VIKING PUMP COMPANY, OF CEDAR FALLS, IOWA

ROTARY PUMP

Application filed October 21, 1929. Serial No. 401,191.

My invention relates to improvements in rotary pumps and motors, and the object of my improvement is to provide release means for entrapped liquids in such devices to reduce wear of the rotating parts, reduce power consumption, increase mechanical efficiency of the device, and prevent possibility of tooth fracture caused by excessive hydraulic pressures from liquid imprisonment at certain places within such devices.

This object I have successfully achieved by the means which are hereinafter described and claimed, and which are illustrated in the accompanying drawings, in which Fig. 1 is a front elevation of a rotary pump with the cylinder cover removed, and with a part broken away. Fig. 2 is an axial vertical longitudinal section of the complete pump, with parts broken away. Fig. 3 is an elevation of the inner face of the cylinder cover showing its liquid relief passage, and Fig. 5 is a similar elevation showing a modified kind of said passage. Fig. 4 is a transverse section of the pump, with parts broken away, taken on the broken line 4-4 of said Fig. 2 and looking in the direction indicated by the arrow. Figs. 6 and 7 are like elevations of a rotary pump in each case having a modified arrangement of intermeshing gears or pistons therein, Fig. 7 showing a pair of relief passages for delivery in one direction only, the Fig. 6 showing these passages arranged and shaped to permit the action of the pump to be reversible.

These drawings illustrate well known types of rotary pumps. My liquid relief means in each case is shown incorporated with the pump, but it is to be understood that such means, modified as may be necessary, may be of any kind and used with any other species of rotary pumps or motors without departing from my invention, or from the protection of the appended claims.

In the pump illustrated herein, Figs. 1 to 5 inclusive, the numeral 1 denotes the pump cylinder whose open front end is closed by a discoidal cylinder-head or cover 17 secured thereon by machine screws 18 removably.

The rear part of the cylinder 1 has an integral and axially apertured diminished

sleeve extension 2 within which is fitted a bushing 9, and the latter together with said extension 2 have communicating apertures 10 to an oil-cup 11 to lubricate a contained shaft 5.

Any suitable packing 12 may be placed in the rear part of the hollow of the extension 2 which is closed by a gland 13. A spline 8 secures a rotor 6 on the shaft 5 within the hollow 3 of the cylinder 1 to fit it circumferentially, the rotor having on its front face inwardly directed crown teeth 7.

The cylinder-head 17 has an outwardly and forwardly directed centrally apertured eccentric boss to receive a headed screw 19. The aperture of said boss and head is coned forwardly and a pintle 20 has a threaded part to seat thereon the nut 19 and to secure the same thereon, the inner face of the head 17 having an annular groove 22 concentric around the pintle to partially receive a bearing bushing 21, a spur-toothed idler 23 being fixedly mounted on the bushing 21, the bushing giving more bearing on the surface of the pintle than the actual width of the idler would normally allow. The idler is positioned within the hollow between the crown teeth of the rotor 6, providing an internal gear, the teeth of the idler successively intermeshing with said crown teeth 7 at the top, as the idler is mounted eccentrically relatively to the rotor. The numeral 26 denotes a crescental boss on the inner face of the head 17 to project into the cylinder cavity 3 to be interposed between the spaced teeth of the idler and rotor at the bottom below the pintle 20, thus closing their interspace there.

The numerals 16 and 15 denote laterally opposite chambers provided in the cylinder, and having terminal ports for communication with pipes not shown to deliver a liquid into the cylinder, and to discharge it therefrom respectively, these chambers also communicating with the cylinder cavity 3 at opposite sides thereof.

Referring to said Fig. 3, the numeral 27 denotes a liquid relief passage formed in the inner face of the cylinder-head 17. The upper end of this passage has a communica-

tion with a longitudinal recess 14 in the upper part of the cylinder.

The passage part 27 extends downwardly circularly at 28 around the idler bushing 21 and terminates at its lower end in a horizontally elongated transverse open hollow 29 of sufficient length that it can at no time be completely covered by a passing gear tooth.

Referring to said Figs. 2 and 4, the numeral 14 denotes a longitudinal rectangular downwardly opening groove or recess in the top of the inner circumferential wall 3 of the cylinder 1 where the wall is an abutment separating the chambers 15 and 16, and which is contacted rotatably by the idler teeth 24 when in full mesh with the crown teeth 7 on the rotor 6. The recess 14 is in communication with the wall passage 27 at the top of the latter and receives the liquid which becomes trapped in the space 33 between the tops of the idler teeth 24, the sides of the rotor teeth 7 and the wall of the abutment.

The sides of the rotor teeth 7 are convex while the sides of the idler teeth 24 are concave to properly mesh in their coacting positions. When a rotor tooth 7 at the top of the cylinder is completely in mesh with the idler teeth 24, there is a cavity at the root of the idler teeth in which is trapped or imprisoned a portion of liquid, which, being incompressible, receives from the intruding rotor tooth 7 a pressure which is communicated through the trapped liquid to the idler and to the pintle 20, exercising excessive frictional pressure upon the latter.

In actual practice and under normal conditions a good rotary pump has a volumetric efficiency of from approximately 90 to 96 per cent, the balance being lost due to what is termed "slippage." A part of this "slippage" is due to the fact that the interdental spaces receiving liquid from the suction port of the pump do not become 100 per cent filled. This is due to the fact that most rotary gear pumps usually must take liquid into the rotating elements against opposing centrifugal force. The interdental spaces therefore which are receding from the suction port contain the larger percent of liquid with the balance a vacuum.

Upon exposure to the discharge port the existing liquid pressure therein replaces the small spaces formerly occupied by the vacuum and intermeshing of the gear teeth begins, whereby the liquid is expelled into the discharge port excepting for the balance of the small percentage termed as "slippage" that becomes trapped between the teeth of the intermeshing gears, causing hammering, excessive wear, much loss of driving power, noise, vibration, and sometimes actual tooth fracture. The liquid then escapes into the suction opening. This liquid is by my device led from the points where trapping occurs to

a neutral area connecting with the tooth spaces that have just receded from the suction opening and which as before mentioned are not completely full, thereby permitting the heretofore entrapped liquid to pass thereto at a much reduced pressure which greatly diminishes the objectionable characteristics previously cited.

Comparative tests between rotary pumps supplied with such passages as above described, prove that such passages serve to greatly enhance the efficiency of the devices in different ways. These tests show that the pumps supplied with these passages require eleven and three quarters per cent less operating power than the unsupplied pumps. Noise, vibration and hammering are immediately greatly reduced and possibility of tooth fracture from the aforesaid reasons made very remote.

Furthermore, in pumps handling very viscous liquids such as tar, glucose, malt syrups and lacquers which naturally resist movement, the spaces between the teeth of the rotating elements receding from the suction opening contain a greater percentage of vacuum than ordinarily due to the movement of the gears not allowing sufficient time for the spaces to become completely filled with such heavy slow moving liquids. Consequently the filling of these vacuum pockets at the discharge opening occurs with a decided impact setting up a very injurious vibration throughout the pump and piping system. This naturally rapidly wears out and dislocates the device. However, due to the relief passage the vacuum pockets are almost completely nullified, greatly diminishing harmful action as described.

In Figs. 6 and 7 are shown like pumps having like intermeshing piston gears 31 and 32 of a well known type, the pump cylinder 1 having opposite receiving and discharge ports 16 and 15 located medially. In this type of pump, see Fig. 6, the gears mesh in such a manner that the root closed cavities at 27 are alternately shifted from one gear to the other, so that a pair of like relief passages 27, 28 and 29, like the passage of Figs. 1 to 4, are employed to successively and alternately receive liquid imprisoned in said cavities. The only difference between the passages of said Figs. 6 and 7 is in the fact that the passages in the device of Fig. 6 are adapted to deliver liquid to a neutral area and conveyed to the discharge port, the device being reversible and functions the same regardless of the direction of pump rotation.

The passages in Fig. 7 are similar to those shown in Fig. 5, being shaped and employed only where the rotations of the gears are unidirectional to deliver to one outlet.

It is obvious that the neutral areas for reception of liquid from the root cavities of intermeshing gear teeth in such devices may

be positioned as desired relative to the different parts thereof which coact therewith, and such relief means may be used with any rotary pump or motor without departing from the invention herein.

Having described my invention, what I claim as new, and desire to secure by Letters Patent, is:

1. A rotary pump or motor, comprising a casing having an inlet port and a discharge port, intermeshing driving and driven pistons in said casing, said pistons being a crown gear and an idler spur gear mounted eccentrically relative to the crown gear and meshing internally therewith, means for closing the interspace between the gears opposite their intermeshing teeth, said casing having a conduit positioned to communicate intermittently successively with the spaces between the intermeshing teeth to release its contents to a neutral area within the device to be conveyed thence to said discharge port, to thus release liquid imprisoned within said spaces, and said conduit having one end part extended and positioned for receiving and preventing the trapping of liquid within the interspace of the outer end of an advancing tooth of said idler spur gear and the wall of the casing before the complete meshing of said tooth with teeth of said crown gear.

2. A rotary pump or motor, having a casing with oppositely located inlet and discharge ports, and intermeshing rotor and idler pistons between said ports, said casing having a relief passage to effect communication successively with the spaces between intermeshed parts of the pistons to receive and release liquid imprisoned between the pistons, and a wall cavity in said casing in communication with said passage for receiving and preventing the trapping of liquid within the interspace of the outer end of an advancing part of the idler piston and the wall of the casing before the complete meshing of said part with a coacting part of the rotor piston.

In testimony whereof I affix my signature.

AMOS VERNER JENSEN.
